B. Anger, ATTORNEY.

UNITED STATES PATENT OFFICE.

WILLIAM G. BERRY AND MAY BERRY, OF CLEVELAND, OHIO.

PISTON FOR INTERNAL-COMBUSTION ENGINES.

Application filed September 14, 1920, Serial No. 410,264. Renewed June 30, 1925.

To all whom it may concern:

Be it known that we, WILLIAM G. BERRY and MAY BERRY, citizens of the United States, residing at 1552 Payne Ave., Cleveland, in the county of Cuyahoga and State of Ohio, have invented a new and useful Piston for Internal-Combustion Engines, of which the following is a specification.

This invention relates to improvements in pistons for internal combustion engines, one object of the invention being to provide an improved piston which effects an economy in the use of the motor fluid, fits tightly in the cylinder and without leakage of oil, which is extremely durable and strong, and which is of much less weight than the pistons of this class heretofore employed.

Another object of the invention is to provide an improved internal combustion motor piston which is made of aluminum.

With the above and other objects in view, the invention consists in the construction, combination and arrangement of devices hereinafter described and claimed.

25 In the accompanying drawings:—

Figure 1 is an elevation of an internal combustion motor piston constructed and arranged in accordance with this invention.

Figure 2 is a vertical central sectional view of the same on a plane at right angles to Figure 1.

Figure 3 is a transverse sectional view of the same on the plane indicated by the line 3—3 of Figure 2.

35 In accordance with this invention, the piston 1 is made of aluminum and constitutes a single casting. An aluminum piston thus constructed is very much lighter as well as very much stronger and more durable than a piston made, as heretofore, of iron or steel.

The head 2 of the piston is provided with circumferential grooves 3 for the reception of piston rings, and the skirt or outer end 4 of the piston is also provided with a similar groove 5 for the reception of a piston ring. Moreover, the skirt is provided with oblique slits 6 which extend thereacross so that the skirt is of open-ring formation and

the slits or cuts tend to close when the piston 50 expands by heat and hence to a considerable extent neutralizes the expansion and minimizes friction between the piston and the bore of the cylinder in which it operates.

The bearings 9 for the pivot pin of the 55 piston are integral with and formed on the skirt, as shown.

The head 2 is provided on its inner side with radial reinforcing ribs 7 which are cast integral with the piston and serve to greatly 60 strengthen the construction of the piston and to enable a considerable economy of material to be effected in the manufacture thereof.

This improved piston is oil-proof, is tight 65 fitting, and saves about ten per cent of gasoline or other motor fluid as compared with pistons of iron or steel such as have been heretofore used.

Our improved piston is oil proof, because 70 it is made to fit tightly in the cylinder, no allowance being required to be made, as in other cylinders. Our piston saves gasoline because it is light and fits tightly in the cylinder.

Moreover, the expansion is endwise to other pistons, the ribs 8 outside expanding in length, while other pistons expand sidewise. Our piston is free from vibration and it 75 enables the engine in which it is used to be 80 run at a higher rate of speed than heretofore.

Having thus described our invention, we claim:—

A piston for an internal combustion motor 85 comprising a head, a skirt of open ring formation spaced from the head, longitudinal ribs arranged in spaced relation and connecting the skirt to the head, each of said ribs having a longitudinal slot and the opening 90 in the skirt ring extending to the outer end of one of the slots, and bearings for a piston rod pivot formed on and carried by the skirt and arranged in the spaces between the longitudinal ribs.

In witness whereof we affix our signatures.

WILLIAM G. BERRY.

MAY BERRY.
